UNITED STATES PATENT OFFICE.

FRANCIS SCHINDLER, OF SCARSDALE, NEW YORK, ASSIGNOR TO BIGELOW CARPET COMPANY, A CORPORATION OF MASSACHUSETTS.

DESIGN FOR A RUG.

41,420.

Specification for Design.

Patented May 30, 1911.

Application filed April 4, 1911. Serial No. 618,943. Term of patent 7 years.

To all whom it may concern:

Be it known that I, FRANCIS SCHINDLER, a citizen of the United States, residing at Scarsdale, in the county of Westchester and State of New York, have invented a new, original, and ornamental Design for a Rug, of which the following is a specification, reference being had to the accompanying drawing, forming part thereof.

The drawing illustrates one quarter of a rug showing my new design, the remaining three quarters being duplicates thereof.

I claim:

The ornamental design for a rug, as shown.
FRANCIS SCHINDLER.
